UNITED STATES PATENT OFFICE

149,446

DESIGN FOR A MOTOR CAR

Julius Rose, Ridgewood, Long Island, N. Y.

Application October 16, 1946, Serial No. 133,988

Term of patent 14 years

(Cl. D14—3)

To all whom it may concern:

Be it known that I, Julius Rose, a citizen of the United States, residing at Ridgewood, Long Island, New York, have invented a new, original, and ornamental Design for Motor Cars, of which the following is a specification, reference being had to the accompanying drawing, forming a part thereof.

Figure 1 is a perspective view of a motor car embodying my new design;

Figure 2 is a front end elevational view thereof; and

Figure 3 is a rear end elevational view thereof. Although the drawing shows only one side of

the motor car, both sides thereof have the same design.

I claim:

The ornamental design for a motor car, as shown and described.

JULIUS ROSE.
